UNITED STATES PATENT OFFICE.

THOMAS R. HAYES, OF MONROVIA, CALIFORNIA.

CHAIR.

Application filed October 20, 1926. Serial No. 142,981.

My invention relates particularly to collapsible or folding chairs of the class in which the seat is composed of flexible material such as a woven fabric, and is especially directed to the means whereby the seat may be connected with its supporting members.

The principal objects of my invention are to provide a folding chair with seat supporting means so constructed and arranged as to tend to relieve the seat from the usual tensile strains incident, in chairs of this type, to the spreading action of the chair frame.

Other objects of my invention are to provide a folding chair with clamping means so associated with a locking element as to positively determine the relative height of the chair seat with respect to the floor upon which the chair rests, as well as the maximum width between the extended side frames.

My invention comprehends such an arrangement of the clamping means as to insure that the chair seat supports and locking elements will be maintained relatively parallel and normal to the legs of the chair frame structure, irrespective of any stretching of the fabric or material of which the chair seat may be formed.

My invention further includes a folding chair in which the seat fabric or material may be removed without effecting the stability of the relatively collapsible members.

My invention is equally applicable to chair frame members that approach and separate laterally toward and from each other and those that fold forward and back with respect to the chair.

The form of my invention as hereinafter described, comprises a chair frame provided with legs upon which a rider plate, having oppositely disposed terminal flanges, is arranged to slide, the rider plates of the legs of the respective frame members being connected by a seat supporting rail rigidly secured thereto and a locking bar of oval cross-section serving as an eccentric and arranged to turn on its axis between the inner flange of the rider plate and the chair leg to effect jamming of the outer flange against said chair leg.

My invention also includes all of the various novel features of construction and arrangement as hereinafter more definitely specified.

In the accompanying drawings, Figure 1 is a perspective view of a collapsible or folding chair conveniently embodying my invention; Fig. 2 is an enlarged fragmentary perspective view showing the details of construction of the rider plate and its associated parts; Fig. 3 is a perspective view of the chair shown in Fig. 1, in its collapsed or folded position; Fig. 4 is a vertical transverse sectional view of the chair extended or spread as shown in Fig. 1, looking toward the front thereof; Fig. 5 is a vertical longitudinal sectional view of a modified form of chair embodying my invention; Fig. 6 is an enlarged fragmentary sectional view taken transversely, as shown in Fig. 4, and showing the details of the rider plate connection.

In said figures, the right frame of the chair comprises the front leg stile 1 and the back leg stile 2, and the left frame comprises the front leg stile 3 and the back leg stile 4, the leg stiles 1 and 2 being connected by the rungs 5 and 6 and the leg stiles 3 and 4 being connected by the rungs 7 and 8 and the arm 9.

The right frame of the chair is provided with a table leaf 10 mounted to swing on the rung 6 and provided with the cleat 12 having pivoted thereto at 13 the leaf supporting bar 15, which, as best shown in Fig. 4, is provided with the notch 16, and is arranged to slide in the flanged guide plate 17, pivoted to the leg stile 1 and serving as a keeper with which the notch 16 may engage to support the table in horizontal position.

When it is desired to drop the table leaf into its vertical or inoperative position, the leaf supporting bar may be forced inwardly, as indicated by the arrow in Fig. 4, to release the notch 16 from its keeper to permit the leaf supporting bar to slide downwardly through the guide 17.

The leg stiles 1 and 2 of the right frame are embraced by the oppositely flanged rider plates 19 and 20 which are connected by the seat supporting rail 22 rigidly secured thereto by the screws 21, and by the eccentric locking bar 23 which is rotatably associated therewith by the screws 25, and which is connected by the trellis bars 26 and 27 with the chair rung 7 upon which said trellis bars are arranged to rotate.

Similarly, the leg stiles 3 and 4 of the left frame are embraced by the oppositely

flanged rider plates 29 and 30, which are connected by the seat supporting rail 32 rigidly secured thereto by the screws 31, and by the eccentric locking bar 33 which 5 is rotatably associated therewith by the screws 25, and which is connected by the trellis bars 36 and 37 with the chair rung 5 upon which said trellis bars are arranged to rotate. As best shown in Figs. 1 and 4, 10 the trellis bars are pivoted together intermediate of their length as at 39.

The seat supporting rails 22 and 32 are arranged to support the seat 40 which may be of any desired form or material, but may 15 preferably be in the form of an endless belt or band of flexible material through the looped ends 41 and 42 of which said rails 22 and 32 extend, as illustrated.

The back leg stiles 2 and 4 of the respective side frames of the chair are extended 20 upwardly to support the back-rest which may preferably be formed in a manner similar to the seat and be composed of an endless band of flexible material 45 through the 25 looped ends 46 and 47 of which the back-rest stays 48 and 49 may extend as shown, said stays being pivoted to the leg stiles 2 and 4, as at 50.

As best shown in Figs. 2 and 6, the rider 30 plates are each provided with opposed parallel inner and outer terminal flanges 52 and 53 respectively, the outer flanges 53 bearing against the outer sides of the leg stiles, and the inner flanges being so spaced 35 from the inner side of said leg stiles as to embrace the ends of the seat rails and locking bars, see Figs. 4 and 6, wherein it will be obvious that when the side frames including the leg stiles are caused to relatively approach, the locking bar 23 will 40 release the rider plate by relieving its frictional engagement with the leg stile such as 19 shown in said figures, and that when said side frames are spread or extended to effect 45 consequent rotation of said locking bar, the eccentrically extended rounded corners 55 and 56 will respectively engage the flange 52 and the inner face of the leg stile, and so tend to jam them apart as to 50 force the flange 53 into frictional engagement with the outer face of the leg stile.

In the form of chair shown in Fig. 5, to which my invention may be readily applied, the back leg stiles 60 are provided with 55 rider plates 61 having the flanges 62 and 63, and are connected with the front legs 65 by the trellis bars or struts 66 which are pivoted at 67 to said legs 65 and at 68 to said leg stiles 60 and which carry the forward 60 seat supporting rail 69 between which and the back seat supporting rail 70 on the rider plates 61 the seat 71 of flexible material may be suspended.

In this form of chair, the front legs 65 65 are directly connected with the locking bar

72 which is rotatably connected with the rider plates 61 and disposed between the inner face of the leg stiles 60 and the flanges 62 of said rider plates, so that when the chair frame members are extended or 70 spread, as illustrated in said figure, the extended corners 75 and 76 of the locking bar 72 will bear against the flanges 62 and inner faces of the leg stiles 60 with such force as to frictionally engage the flanges 63 with 75 the outer faces of the leg stiles 60, and when said chair frame members are caused to approach or collapse, the locking bar will be rotated to release said rider plates and permit them to freely slide upwardly on their 80 respective leg stiles.

My invention is advantageous in that by the employment of rider plates as contemplated, the stretching of the canvas or other flexible material forming the seat effect no 85 influence upon the working members of the chair, and the seat may be removed from the chair frames without affecting their relation. Furthermore, the weight of a person on the seat of the chair tends to draw the 90 flange of the rider plates firmly against leg stiles, and also tends to crowd the locking bar to the opposite side of the leg stiles, thus pinching them between the two. This action is efficiently effected regardless of any 95 stretching of the seat material and also relieves the weight from the screws at the respective ends of the locking bar. The greater the weight on the seat of the chair, the more rigid it becomes, thereby making 100 it at such times as solid and firm as a permanent chair. Such construction also permits the free adjustment of the chair members without conflicting with the table leaf structure.

I do not desire to limit my invention to the precise details of construction and arrangement as herein set forth, as it is obvious that various modifications may be made therein without departing from the 110 essential features of my invention as defined in the appended claims.

Having thus described my invention, I claim:

1. A collapsible chair comprising relatively movable frames having leg stiles upon which rider plates having terminal flanges are arranged to slide, a seat rail rigidly connecting the oppositely disposed rider plates and arranged to support a seat formed of flexible material, and a locking bar rotatably associated with said rider plates arranged to frictionally engage said rider plates with said leg stiles.

2. A collapsible chair comprising relatively movable frames having leg stiles, rider plates each having relatively parallel flanges arranged to slidably embrace said leg stiles, an eccentric locking bar rotatably associated with said rider plates and ar- 130

ranged to effect frictional engagement of said rider plates with their respective leg stiles upon the spreading of said frames.

3. A collapsible chair comprising relatively movable frames having leg stiles, rider plates each having relative opposite parallel flanges arranged to slidably embrace said leg stiles, an eccentric locking bar rotatably associated with said rider plates 10 arranged to effect the engagement and release of said rider plates with their respective leg stiles, upon the extension and approach of said frames.

4. A collapsible chair comprising relatively movable frames having leg stiles, rider plates each having relative opposite parallel flanges arranged to slidably embrace said leg stiles, an eccentric locking bar rotatably associated with said rider plates 15 20 plates arranged to effect the engagement and release of said rider plates with their respective leg stiles, upon the extension and approach of said frames, and seat supporting rails carried by said rider plates independently of said locking bars.

5. A collapsible chair comprising relatively movable frames each having a forward leg stile and a rearward leg stile, a rider plate having opposite relatively parallel flanges arranged to slidably embrace each of said leg stiles, an eccentric locking bar rotatably engaged with opposed rider plates and extended between one of the flanges of said rider plates and the leg stile, and means 30 35 connecting said locking bar with the opposed relatively movable frame arranged to effect the rotation of said locking bar whereby the relative separation of said frames effect rotation of said locking bar to frictionally engage said rider with its leg stile, and the relative approach of said frame effects a release of said frictional engagement.

6. A collapsible chair comprising relatively movable frames each having leg stiles, rider plates having opposite relatively parallel flanges arranged to slidably embrace said leg stiles of one of said frames, an eccentric locking bar rotatably engaged

between opposite leg stiles and one of the 50 flanges of their respective rider plates, said locking bar being connected with the other of said frames to effect its rotation when said frames are relatively moved, whereby the extension of said frames effects frictional engagement of said rider plates with their respective leg stiles, and the approach of said frames effects release of said frictional engagement. 55

7. A collapsible chair comprising relatively movable frames each having leg stiles, a table leaf hingedly connected with said stiles, and a seat supporting structure movable up and down on said stiles and arranged to avoid interference with said table 60 65 leaf, comprising flanged rider plates arranged to slide on said stiles and connected by a seat supporting rail, and having an eccentric locking bar disposed between said leg stiles and the flanges of the respective 70 rider plates, which when rotated effects frictional engagement of said structure with said stiles.

8. A collapsible chair comprising relatively movable frames each having leg stiles, 75 and a seat supporting structure comprising rider plates respectively having oppositely disposed parallel flanges slidably embracing said leg stiles, a seat supporting rail free from said leg stiles, connecting said 80 rider plates, and an eccentric locking bar connected with said rider plates and their respective leg stiles, arranged to be turned to jam said rider plates into frictional engagement with said leg stiles. 85

9. A collapsible chair structure comprising rider plates having oppositely disposed terminal flanges, a seat supporting rail connecting said rider plates between said flanges, and a rotatable eccentric locking bar 90 connecting said rider plates independently of said seat rail, and disposed between said flanges and adjacent to one of the flanges of the respective rider plates.

In witness whereof, I have hereunto set my hand this 30th day of September, A. D. 1926.

THOMAS R. HAYES.
